UNITED STATES PATENT OFFICE.

HENRY C. JOHNSON AND JESSE B. MOORE, OF EL DORADO, ARKANSAS.

DESIGN FOR A BUCKLE.

SPECIFICATION forming part of Design No. 16,347, dated October 20, 1885.

Application filed August 5, 1885. Serial No. 173,636. Term of patent 14 years.

To all whom it may concern:

Be it known that we, HENRY C. JOHNSON and JESSE B. MOORE, citizens of the United States, residing at El Dorado, in the county of Union and State of Arkansas, have invented a new and original Design in Buckles; and we do declare the following to be a full, clear, and exact description of the invention, such as will enable others skilled in the art to which it appertains to make and use the same, reference being had to the accompanying drawing, and to the letters and figures of reference marked thereon, which form a part of this specification.

15 The accompanying drawing illustrates our new and original design for a buckle, the figure being a perspective of the same.

The design of this buckle consists of four lateral bars, a center strap and pin, two upright bars, and two parallelogram ends, and is skeleton and oblong.

20 The two top lateral bars, 4, are a little longer than the two bottom lateral bars, 5, so that when the ends 1 and 3 are affixed to the

said lateral bars the top of the buckle is a little 25 longer than the bottom.

The center strap, 2, has a cone-shaped pin, 6, attached to its upper face at its middle, the large end of the said pin being down.

25 The upright side straps, 7, are integral with 30 the middle of the lateral bars 4 and 5.

The inner and outer corners of this buckle are made a little rounding.

Having described our new design for a buckle, what we claim is--

35 A design for a buckle rectangular in shape, approximately square in cross section, having side bars, 7, cross-bar 2, central pin, 6, vertical sides, and inclined ends with open panels, the whole being of a skeleton form, as 40 shown.

In testimony whereof we affix our signatures in presence of two witnesses.

HENRY C. JOHNSON.
JESSE B. MOORE.
